CLYDE J. MYERS, OF INDIANAPOLIS, INDIANA, ASSIGNOR TO SWARTZ ELECTRIC COMPANY, OF INDIANAPOLIS, INDIANA, A CORPORATION OF INDIANA.

TIMER FOR IGNITION-CIRCUITS OF ENGINES.

1,361,088.

Specification of Letters Patent.

Patented Dec. 7, 1920.

Application filed April 6, 1918. Serial No. 227,068.

To all whom it may concern:

Be it known that I, CLYDE J. MYERS, a citizen of the United States, residing at Indianapolis, Marion county, and State of Indiana, have invented and discovered certain new and useful Improvements in Timers for Ignition-Circuits of Engines, of which the following is a specification.

My invention relates to timers for ignition circuits for internal combustion engines. The object of the invention is to provide a common instrumentality which may be interposed between a source of direct current spark producing elements and both draw a high tension for the ignition circuit from the source of direct current and at the same time provide means whereby the timing of the explosions may be adjusted.

With this object in view my invention is embodied in preferable form in the construction and arrangement hereinafter described and illustrated in the accompanying drawings.

The drawing is a side view in elevation, partly diagrammatic of a dynamo electric machine and spark creating elements as shown in my invention applied thereto.

Referring to the drawings, 1 indicates the shaft of a dynamo electric machine which may be either a generator or a motor, and 2, indicates the commutator thereof against which bears the direct current commutator brush 3. Carried on the shaft and revolving with the commutator is a contact carrying element consisting of a ring of non-conducting material, carrying a timing segment 5 which is connected by a connector 6 with one segment of the commutator. The ring 4 and the timing segment 5 carried on the ring are relatively adjustable circumferentially to change the timing of the ignition spark by means of set screw 7. Adapted to bear on the surface of the ring of insulating material and to contact incidentally with the timing segment carried there-

by is a collecting brush 8. The brushes 8 and 3 are in circuit with a vibrator coil 9 and a spark plug 10.

In the revolution of the commutator the insulated segment carrying ring will revolve with the commutator and the contact segment will be carried under the collecting brush 8, thus not only drawing current for the high tension ignition circuit directly from the direct current commutator, but also directly establishing the ignition circuit through the spark plug.

This arrangement dispenses with the necessity for the use of a separate magneto and timer customarily employed, or other means of special character for producing a high tension current.

Having thus described my invention, what I claim is:

1. In combination with a dynamo electric machine, a commutator therefor, a member revolving with the commutator and carrying a brush contact, said contact having connection with a segment of the commutator, a collecting brush adapted to bear on said revolving member, an ignition circuit and means for adjusting said brush contact circumferentially of said member to change the timing.

2. In combination with a dynamo electric machine, a commutator therefor, an insulating member carrying a brush contact, said contact having connection with a segment of said commutator, and means for adjusting the position of the said insulating member circumferentially of said commutator to change the timing.

In witness whereof, I have hereunto set my hand and seal at Indianapolis this 23rd day of March, A. D. nineteen hundred and eighteen.

CLYDE J. MYERS. [L. S.]

Witnesses:

C. K. BURDICK,
W. B. SEFTON.
